UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

STOKER-BLOWER CONTROL MECHANISM.

Application filed February 18, 1921. Serial No. 446,143.

My invention relates to furnaces and more particularly to devices for controlling its operation, and it has for an object to provide an improved and efficient arrangement for effectively controlling the operation of an air fan associated with the furnace.

Another object is to provide an improved pressure-responsive apparatus for controlling the operation of an air fan.

Another object is to provide pressure-responsive apparatus for controlling the operation of an air fan which is responsive to a pressure derived from the flow of air to said fan.

Still another object is to provide an apparatus for controlling the operation of an air fan which is controlled by a pressure derived from either steam flow or feed water flow, and the flow of air to said fan.

These and other objects are effected by my invention, as will be apparent from the following description and claims taken in connection with the accompanying drawings, forming a part of this application, in which:—

Fig. 1 is a diagrammatic view, partially in section, of an apparatus embodying my invention; and

Fig. 2 is a diagrammatic illustration of the apparatus shown in Fig. 1 applied to a steam generator.

In the operation of power plants having stoker furnaces, regulating means must be provided for the fuel-feeding and draft-producing apparatus which shall be responsive to the requirements of the prime movers for steam. Arrangements of Pitot tubes and Venturi elements have been installed in the steam mains, leading from the boilers, to operate with diaphragm pressure motors to effect a regulation of the heat-producing elements supplied to a boiler furnace in accordance with requirements for steam. I have discovered that more reliable and satisfactory results may be attained with an apparatus constructed in accordance with my invention, employing an apparatus of this general character which regulates the amount of air supply to a boiler furnace directly in ac-

cordance with the steam requirements placed upon the boiler, utilizing functions of either the rate at which steam is drawn from the boiler, or the rate at which feed water is fed into the boiler for securing this regulating effect.

Referring to the drawing for a more detailed description of my invention, 10 indicates a Venturi element located in a conduit 11 communicating with the boiler. As pointed out above, the conduit 11 may be either a steam main or a feed-water line or main. The throat of the Venturi element is connected by means of a conduit 12 with a chamber 13 of a diaphragm motor 14. The conduit 11 near the entrance to the Venturi element communicates through a conduit 15 with a chamber 16 of the diaphragm motor 14. A diaphragm 17 of the motor may be of any suitable construction. The diaphragm 17 of the motor is moved in one direction or the other in accordance with variations of the pressure due to the changes in the rate of flow through the conduit 11 in a manner well understood by those skilled in this art. The diaphragm 17 is connected by a link 18 to one end of a rocker arm 19. The other end of this rocker arm is connected to a link 20 which in turn is attached to the diaphragm 21 of a diaphragm motor 22. The diaphragm motor 22 is separated into two chambers 22' and 23 by the diaphragm 21. The chamber 22' is subject to the pressure of the atmosphere and the chamber 23 communicates through a conduit 24 with a blower casing 25 at the point of lowest absolute pressure when a propeller 26 of the blower is rotating.

The propeller 26 is driven through a shaft 27 by means of a turbine 28 or similar drive means. A valve 29, located in a conduit 30 supplying motive fluid to the turbine, is adapted to be controlled by a piston 31 located in a cylinder 32 and connected to the valve by means of a rod 33. A chamber 34 above the piston 31 communicates with a cylinder 35 of a relay mechanism through a conduit 36, and a chamber 37 below the piston 31 communicates with the cylinder 35 through a conduit 38. Conduits 39 and 40

lead into the cylinder 35 from a suitable supply of fluid under pressure and a conduit 41 leading from the cylinder 35 serves as an exhaust for the pressure fluid. Mounted in the cylinder 35 are four pistons, 42, 43, 44 and 45 which are connected to a rod 46 which in turn forms a pivot for the rocker arm 19.

In Fig. 2 I show the apparatus described and illustrated in Fig. 1 arranged in a boiler installation. The conduit 11 connects to a boiler 50 under which is placed a stoker furnace 51, fuel-feeding mechanism 52 of any desired type is employed to supply fuel to the furnace. The apparatus herein shown 15 may be readily operated by a flow of steam or of feed water through the conduit 11, each of which are indicative of the boiler requirements for steam.

The blower casing 25 connects with an air duct 53 which enters the furnace 51 through an opening 54 beneath the same.

Having thus described an apparatus constructed in accordance with my invention, the operation is as follows: When the 25 velocity of the fluid and consequently its volume, passing through the conduit 11 increases, the pressure at the throat of the Venturi element drops, producing a corresponding drop in the pressure in the chamber 13 of the diaphragm motor 14. The diaphragm 17 then moves upwardly and causes the pistons 43 and 44 to move upwardly and to uncover the ends of the conduits 36 and 38 respectively, leading to the cylinder 35. Fluid under pressure, preferably oil, from the conduit 40 then enters the conduit 38 and the chamber 37 below the piston 31 and some of the pressure fluid in the oil chamber 34 above the piston is permitted to escape to the exhaust 41. This increased pressure thus brought to bear on the lower side of the piston 31 forces the piston 31 up, thus tending to open wider the valve 29 in the conduit 30 supplying steam to the 40 turbine 28. The speed of the blower 26 and the velocity of the air passing through the casing 25 are then increased, causing a decreased pressure in the conduit 24 and in the chamber 23 which causes the diaphragm 21 in the motor 22 to fall, the atmospheric pressure above the diaphragm 21 remaining constant. This downward movement of the diaphragm 21 acting through the link 20, rocker arm 19, and rod 46 produces a proportional downward movement of the pistons 43 and 44, closing the end of the conduits 36 and 38 and thereby restoring equilibrium in the relay mechanism.

Similarly, when the volume of fluid passing through the pipe line 11 decreases, the pressure at the throat of the Venturi element increases, producing a corresponding increase of pressure in the chamber 13 of the diaphragm motor 14. This change of

pressure within the chambers of the diaphragm motor 14 produces a downward movement of the diaphragm 17, which, acting through the link 18, lever 19, and rod 46, causes the pistons 43 and 44 to move downwardly and to uncover the ends of the conduits 36 and 38 respectively. Fluid under pressure from conduit 39 will then enter the passage 36 and the chamber 34 above the piston 31 and some of the pressure fluid beneath the piston 31 will be permitted to escape to the exhaust conduit 41. The increased pressure thus brought to bear on the upper side of the piston 31 forces the piston down, tending to close the valve 29 in the conduit 30 supplying steam to the turbine 28. The speed of the blower and consequently the velocity of the air passing therethrough are then decreased, resulting in an increase in pressure in the conduit 24 and the chamber 23. This increased pressure allows a return upward movement of the diaphragm 21 which, acting through the link 20, rocker arm 19 and rod 46, causes an upward movement of the pistons 43 and 44 and closes the conduits 36 and 38, thereby 90 restoring equilibrium in the relay mechanism.

On the other hand, variation in the velocity of the flow of air to the furnace reacts through the relay mechanism to establish a uniform speed of the blower thus delivering a uniform air supply. The varying conditions of air are conversely due to the resistance to the flow of air through the fuel bed. A heavy fuel bed retards the passage of air therethrough and as a result the velocity of air through the blower is diminished. The diminution of air velocity causes a decrease in suction at the throat of tube 24 and the pressure increases in the tube 24 and chamber 23 and thus raises the disc which will react to raise the fluid piston 46 and cause an increased flow of air to the furnace. The pressure motor 14 and 22 are constructed to give a uniform regulation of air supply to the furnace over a wide range of requirements.

While it is to be understood that other well known mechanisms for operating in accordance with the volume of the fluid passing through the pipe line 11 by means of pressure differences may be employed, as for example a Pitot tube; the Venturi element is particularly adapted for use with a fan blower. In a Venturi element the pressure drop at the throat is proportional to the square of the velocity, or approximately to the square of the volume of the fluid flowing therethrough. The suction pressure of a fan or blower is also proportional to 125 the square of the velocity or volume of air flowing therethrough. It is thus seen that the rate of flow through each of these devices

is proportional to the square of the velocity of medium flowing through them, and consequently, in applicant's apparatus, the air flow will at all times be substantially directly proportional to the flow of the fluid through pipe line 11.

The fan 26 is shown as being of the propeller type and is also shown as being mounted for rotation in the throat portion of a converging-diverging passage of the fan housing 25. It is to be observed, however, that my invention in certain of its broader aspects is not limited to this particular type of fan and housing, for it might equally as well be applied to any type of fan having a housing which is provided with a constricted inlet opening for supplying air to said fan. By "constricted inlet opening" I mean constricted with relation to the space within which the fan is positioned.

While I have shown my invention in but one form, it will be obvious to those skilled in the art that it is not so limited but is susceptible of various other changes and modifications, without departing from the spirit thereof and I desire, therefore, that only such limitations shall be placed thereupon as are imposed by the prior art or as are specifically set forth in the appended claims.

What I claim is:

1. In a relay heat regulating mechanism for boiler furnaces, a conduit communicating with the boiler, an air supply device and means cooperatively associated with the conduit and air supply device for controlling the speed of said air supply device by a regulating effect derivable both from the velocity of fluid flowing through the conduit and from the velocity of air supply.

2. In combination with a boiler furnace provided with air supply means and fluid delivery means, of control means operable for adjustment of the rate of air supply, means for deriving a primary controlling force which is a function of the rate of fluid passing through the delivery means, additional means for deriving a secondary controlling force which is a function of the rate of air passing to the furnace and means for combining said forces differentially for application to said control means.

3. In combination with a stoker furnace provided with air supplying means and fluid supply means, of control means operable for the adjustment of the rate of air supply, means for deriving a controlling force which is substantially proportional to a function of the rate of air supply to said furnace, additional means for deriving a controlling force which is substantially proportional to a function of the rate of fluid supply associated with the boiler, and means for combining said forces differentially for application to said control means.

4. In a stoker furnace mechanism for vapor generators, the combination of a fluid delivery main, a blower for supplying air to the generator, a motor to drive the blower and means for controlling the speed of the motor responsive to the velocity of the air passing through the blower and velocity of fluid passing through the main.

5. In a boiler furnace having a stoker and a fluid delivery conduit connected to the boiler, the combination of a blower for delivering air to the furnace, a relay mechanism connected to the fluid conduit and the blower for controlling the speed of the blower, said mechanism comprising a diaphragm motor actuated by the velocity of fluid flowing through the conduit, a second diaphragm motor actuated by the velocity of air through the blower and a means associated with said diaphragm motors whereby the velocity of air delivered by the blower is directly proportional to the velocity of fluid through the conduit.

6. In a boiler furnace having a stoker and a fluid supply main connected to the boiler, an air supply means for the furnace, a regulating device for the air supply means comprising a diaphragm motor actuated by the velocity of fluid passing through the main, a second diaphragm motor actuated by the velocity of air passing through the air supply means, connecting means between said motors and means associated with said connecting means whereby the rate of air passing through the blower is a function of the rate of fluid passing through the conduit.

7. In a relay heat mechanism for boiler furnaces, a conduit communicating with the boiler, an air supply device and means cooperatively associated with the conduit and air supply device for controlling the rate of air supply to the furnace by a regulating effect derivable both from velocity of fluid flow through the conduit and the pressure in said air supply device.

8. The combination with a furnace, of a housing defining a converging-diverging passage, a propeller type fan mounted coaxially of the housing and within the throat portion thereof, pressure responsive means for regulating the speed of the fan, conduit means connecting the throat portion of the housing with the pressure responsive means, and other conduit means for conveying air from the housing to the furnace.

9. In an air supply means for a furnace, a housing defining a converging-diverging passage, a propeller type fan mounted in the throat of the passage and coaxially thereof, driving means for the fan, means responsive to pressure for controlling the speed of the driving means, and conduit means connecting the throat portion of the passage with the pressure responsive means for affecting the operation of the latter.

10. In combination with a furnace, a fan, a housing enclosing said fan and having a constricted inlet opening for supplying air to said fan, pressure-responsive means for regulating the speed of the fan, conduit means connecting the constricted inlet opening in the housing with the pressure-respons-
sive means, and other conduit means for conveying air from the housing to the furnace. In testimony whereof, I have hereunto ¹⁰ subscribed my name this 31st day of January, 1921.

HENRY F. SCHMIDT.
